UNITED STATES PATENT OFFICE.

SAMUEL L. DIVEN, OF CARLISLE, PENNSYLVANIA.

LACING-STUD.

No. 833,514.

Specification of Letters Patent.

Patented Oct. 16, 1906.

Application filed January 15, 1906. Serial No. 296,192.

To all whom it may concern:

Be it known that I, SAMUEL L. DIVEN, a citizen of the United States, residing at Carlisle, in the county of Cumberland and State 5 of Pennsylvania, have invented a new and useful Lacing-Stud, of which the following is a specification.

This invention, while relating more particularly to lacing-studs for shoes, is not limited 10 thereto, but is clearly applicable to gloves and various other articles with which laces are employed.

One of the principal objects is to provide a simple and novel device of the above character 15 that will permit the ready introduction and removal of a lace and when the lace is in place therein will have no portion that will engage or catch upon fabric and the like.

A further object is to provide a retaining 20 device or closure for the usual lace-receiving slot that is moved to operative position by the introduction of the lace into the stud, is held in operative position by said lace, and is freed or moved to inoperative position upon 25 the removal of the lace from the stud.

The preferred embodiment of the invention is illustrated in the accompanying drawings, wherein—

Figure 1 is a perspective view of a stud 30 constructed in accordance with the present invention, the same being illustrated on an enlarged scale. Fig. 2 is a vertical sectional view therethrough. Fig. 3 is a similar view showing the relation of the parts when the 35 lace is in place. Fig. 4 is a top plan view of the stud.

Like numerals of reference designate corresponding parts in all the figures of the drawings.

In the embodiment illustrated a substantially 40 spherical head 5 is employed, which is preferably, though not necessarily, substantially solid. This head is provided with a stud 6, which is hollow, in order that it may 45 be readily upset for the purpose of fastening the device to an article. The head 5 is provided with a substantially vertical slot 7. The transverse lace-receiving slot 8, that intersects the slot 7, is disposed at an inclination, the slot 8 being provided with an outer 50 open end, forming a mouth.

A retaining device in the form of a disk 9 is located in the vertical slot 7 and is pivoted to the head 5, a suitable pivot-pin 10 passing 55 therethrough and through the disk. This pin, which is clearly shown in Figs. 2 and 3,

is disposed in line with and in rear of the slot 8. The disk 9 is also provided with a lace-receiving slot 11, which slot is preferably of comparatively great width and is provided 60 with an offset inlet-mouth 12. The slot 11 is preferably disposed tangentially to the pivot 10, and the shape thereof forms an outer overhanging and depending bill 13, that is movable across the outer end or mouth of the 65 head-slot 8 and constitutes a keeper element. Because of the peculiar arrangement it will thus be seen that when the mouth 12 of the retaining-disk registers with the mouth of the slot 8 the slot 11 is out of 70 register with said slot 8, as shown in Fig. 2. On the other hand, when the mouths are out of register, as shown in Fig. 3, then the slots are in register. Because of this arrangement the lower wall 14 of the slot 11 is movable 75 across the slot 8 and constitutes a bearing element or wall for the lace, the wall 14 and the bill 13 alternately moving across the slot 8 as the disk is swung in opposite directions. The movement of the said disk is limited in 80 one direction by a shoulder 15, that abuts against a shoulder 16, formed on the rear portion of the head, and its movement in the opposite direction is limited by the end of the bill 13 abutting against the lower wall of the 85 slot 8, as illustrated in Fig. 3. By having the slot 11 enlarged it will be noted that the portion of the disk 9 on the opposite side of the pivot will be heavier and will overbalance the front portion, thus normally holding the 90 parts in the position shown in Fig. 2. Therefore it will be apparent that if a lace is introduced into the slot 8 it will strike the outer beveled portion of the lower wall 14 and sliding along said lower wall bring the slots 11 95 into register with the slots 8. The resultant movement will therefore cause the tongue 13 to be projected across the outer end of the slot 8, thereby closing said slot against ingress of any fabric or portion of an article of 100 clothing, so that there is no danger of the same becoming caught and torn thereby. The introduction of the lace therefore causes the automatic closing of the slot and holds the bill across the same. As soon, however, 105 as the lace is moved outwardly the bill will automatically raise and permit the detachment of the lace, the parts reassuming their normal position, as shown in Fig. 2, in which they will be held by the overbalancing arrangement of the disk, as already described.

It will thus be seen that an exceedingly

simple device is provided, which may be employed in a variety of ways and which will not catch or injure anything as long as a lace is in place therein.

From the foregoing it is thought that the construction, operation, and many advantages of the herein-described invention will be apparent to those skilled in the art without further description, and it will be understood that various changes in the size, shape, proportion, and minor details of construction may be resorted to within the scope of the appended claims without departing from the spirit or sacrificing any of the advantages of the invention.

Having thus fully described my invention, what I claim as new, and desire to secure by Letters Patent, is—

1. In a stud of the character described, the combination with a head having a slot provided with an open mouth, of a retaining device movably associated with the head and having a slot provided with an open mouth, the slot of the retaining device registering with the slot of the head when the respective mouths are out of register, said mouths registering with each other when the slots are disposed out of substantial register.

2. In a stud of the character described, the combination with a head having a slot provided with an open mouth, of a retaining device movably associated with the head and having a slot provided with an offset open mouth movable into and out of register with the mouth of the head-slot, the slot of the retaining device registering with the slot of the head when the respective mouths are out of register, and one of the walls of the retaining slot being in the head-slot when the mouths are in register.

3. In a stud of the character described, the combination with a head, of a retaining device pivotally mounted on the head, said head having a slot extending radially into the same from one side and toward the pivot-axis of the retaining device, said retaining device also having a slot extending into the same from one side, the bottom of said slot being in a line that passes above the pivot-axis.

4. In a stud of the character described, the combination with a head having a lace-receiving slot, of a retaining device pivotally mounted therein and having a lace-receiving

slot that is movable into register with the slot of the head, said retaining device having an overhanging bill that is movable across the outer end of the head-slot, and furthermore having a slot-wall borne against by the lace when introduced into the head-slot to retain the bill across said head-slot, said retaining device being overbalanced to normally maintain the bill out of the head-slot and the bearing-wall in said head-slot.

5. In a stud of the character described, the combination with a head having a lace-receiving slot, of a retaining device pivotally mounted within the head and having a slot, said device having a keeper and bearing elements on opposite sides of the slot, which elements alternately move into the head-slot from opposite sides thereof upon the opposite movements of the retaining device.

6. In a stud of the character described, the combination with a head having a lace-receiving slot, of a retaining device pivotally mounted within the head and having a wall, said device having keeper and bearing elements on opposite sides of the slot, which elements alternately move into the head-slot from opposite sides thereof upon the opposite movements of the retaining device, and means for limiting the pivotal movement of the retaining device.

7. In a stud of the character described, the combination with a head having a stud, a slot extending therein in one direction, and an inclined slot disposed transversely of the first-mentioned slot, of a retaining-disk located in the first-mentioned slot and pivoted to the head, said disk having a slot that is movable into and out of register with the inclined slot of the head, and an overhanging retaining-bill arranged at the outer end of the disk slot and movable across the outer portion of the inclined head-slot when the two slots are in register, one of the walls of said disk slot being movable into the inclined head-slot when the retaining-bill moves out of the same.

In testimony that I claim the foregoing as my own I have hereto affixed my signature in the presence of two witnesses.

SAMUEL L. DIVEN.
